UNITED STATES PATENT OFFICE.

RUSSELL CLINE ROSHON, OF PARNASSUS, PENNSYLVANIA.

BOWLING ALLEY.

Application filed December 5, 1927. Serial No. 237,885.

This invention relates to bowling alleys and has particular reference to means for resetting the pins, an object being to provide means located at the players' end of the alley 5 whereby the pins may be properly set without employing pin boys for this purpose.

Another object of the invention is the provision of means for automatically returning the balls to the players so that the game may 10 be played with a minimum amount of expense.

Another object of the invention is the provision of a novel pin resetting mechanism, whereby any number of pins knocked down 15 may be reset with any remaining pins at the end of each play, the resetting of all of the pins being simultaneously effected by means of a single operating lever.

With the above and other objects in view, 20 the invention further includes the following novel features and details of construction, to be hereinafter more fully described, illustrated in the accompanying drawings and pointed out in the appended claims.

25 In the drawings:—

Figure 1 is a sectional view taken through a bowling alley equipped with the invention, the invention being shown in elevation.

30 Figure 2 is a fragmentary top plan view of the cabinet which houses the operating mechanism, the resetting drum being shown in plan view.

35 Figure 3 is an enlarged sectional view taken through the cabinet with the mechanism in normal or set position.

Figure 4 is a similar view showing the position of the mechanism when a pin has been raised.

40 Figure 5 is a view similar to Figure 4 showing the mechanism reset and the position of the pin before it moves downward.

Figure 6 is a section on the line 6—6 of Figure 3.

45 Figure 7 is a detail plan view of one of the lever carried pulleys.

Figure 8 is a fragmentary perspective view showing a portion of the alley and ball pit floor.

50 Referring to the drawings in detail where-in like characters of reference denote corresponding parts, the reference character 10 indicates the floor of the alley, 11 the ball pit floor and 12 the usual swinging padded back, while the pins are indicated at 13. 55 These pins may represent duck pins, ten pins

or nine pins, the game being played with the usual balls (not shown).

In order to reset the pins there is provided a resetting mechanism which includes a resetting unit 14 which is individual to each 60 pin. These units are housed within a cabinet 15 and the latter is provided with panels or partitions 16 which separate the units. The bottom of the cabinet is indicated at 17 and this bottom is provided with openings 18, 65 one of these openings being provided for each pin. The openings are of such size as to permit the pins to partly enter the cabinet, the pins being provided with an annular preferably rubber buffer 19 which provides a stop 70 to limit inward movement of the pins.

Each pin is provided with a cable 20, one end of the cable being secured to the pin, with the cable extending upward through one of the openings and having its upper end stationarily anchored within the cabinet as 75 shown at 21.

Pivotedly mounted within the cabinet upon one of the partitions 16 as shown at 22 is a 80 lever 23 which carries at its upper end a grooved pulley 24, the cable 20 passing around this pulley and through a guard 25. The lever 23 is yieldingly pulled in one direction by means of a spring 26, one end of which is secured to the lever and the opposite 85 end to a peg or pin on the panel at the upper left hand corner of the cabinet. Normally, the lever 23 is held against pivotal movement by means of a pivotally mounted latch 27, the pivot of which is shown at 28. One 90 end of this latch carries a hook 29 which engages a stud 30 carried by the lever 23 a weight 31 which is secured to the other end of the lever acting to hold the latch in such engagement. Extending downwardly from the latch 27 is an arm 32 and this arm has 95 extending therefrom a stud 33 which is normally spaced from and adapted to be engaged by a lever 34 which is mounted upon the pivot 22. This lever carries at its outer end a pulley 36 around which the cable 20 passes, the pulley being provided with a guard 39 to retain the cable in position. The cable 20 also passes

100 around a stationary pulley 40 which is positioned below the pulley 24, while an additional pulley 41 acts to guide the cable to the pulley 36. A guide pulley 42 is arranged above the opening in the bottom of the cabinet through which the cable 20 passes. This 105 mechanism is duplicated within the cabinet 110

for each of the pins. A stop pin 43 limits upward pivotal movement of the latch 27.

Secured to each of the levers 34 is a cable 44. This cable passes through an opening 5 provided in the cabinet and is guided over a pulley 45. The outer ends of these cables 44 are wound upon a drum 46 which is mounted in suitable bearings 47 and is located within an extension 48 at the rear of the cabinet 15.

10 The drum 46 is provided with a reduced portion 49 and wound upon this reduced portion is a cable 50. This cable extends downward around a pulley 51 arranged at the rear of the alley and extends forward and passes 15 upward around a pulley 52. The cable 50 then passes around a guide pulley 53 and has its end secured to an operating lever 54 which is pivotally mounted as shown at 55 in a stand arranged preferably at the right of the 20 players' end of the alley. This lever is yieldingly maintained in an upright position by means of springs 56 arranged at each side of the lever at the base.

Normally, the parts are arranged as shown 25 in Figure 1 of the drawings with the pins in set position. One of these pins is shown in Figure 3 of the drawings with the mechanism set. When a ball strikes one or more of the pins with sufficient force to displace it 30 or to cause it to strike other of the pins, the pin or pins so struck will be automatically raised to the position shown in Figure 4 of the drawings. This is due to the fact that the impact on the pin will draw upon the cable 35 20 and by reference to Figure 3 of the drawings it will be seen that a pull upon the cable 20 will cause the lever 34 which may be termed the releasing lever, to engage the stud 33 on the latch 27. This will pull the latch downward 40 against the action of the weight 31 and release the hook end from the pin 30. The lever 23 will thus be released and will be moved to the position shown in Figure 4 by the tension of the spring 26. This will cause 45 the lever 23 to pull upon the cable 20 to raise or hoist the pin. This action takes place in the mechanism for each of the pins struck. The lever 34 remains in the position shown in Figures 3 and 4.

50 The cables 44 and 50 are wound upon the drum in reverse directions, and in order to reset the mechanism and consequently the pins, the lever 54 is operated to pull upon the cable 50. This will rotate the drum 46 in a direction to wind the cables 44 upon the drum, all of the cables being simultaneously wound. The winding of the cables 44 upon the drum will cause a pull upon these cables so as to move the lever 34 to the position shown in 55 Figure 5. As both ends of the cables of the raised pins are in effect stationarily anchored, the pull upon the cables 20 due to the action of the lever 34 will move the lever 23 from the 60 position shown in Figure 4 to the position shown in Figure 5, whereupon the pin or stud 65

30 will again be engaged by the latch 27. Should any of the pins be left in position upon the alley at the end of the play, these remaining pins will then be raised through the movement of the lever 34, and when pull upon the 70 operating lever 54 is released and the lever is permitted to return to its normal vertical position, the weight of the pins 13 will cause the pins to move downward, and as the tension upon the cable 44 has been released, the 75 levers 34 will be returned to the position shown in Figure 3. These levers 34 perform the function of release and resetting levers, in that they act initially to release the hoisting lever 23 and to afterward pull upon the 80 cables 20 to reset these hoisting levers.

In order to return the balls to the players, the floor pit 11 of the alley inclines transversely toward a gutter 57. This gutter inclines from the pin end of the alley to the 85 players' end, so that the balls will roll transversely of the alley along the floor of the pit and will then roll longitudinally to the players. All that is necessary to continue the play is to operate the lever 54 at the end of each 90 play, so that the expense and annoyance, together with danger of injury to the pin boys, are eliminated.

The invention is susceptible of various 95 changes in its form, proportions and minor details of construction and the right is herein reserved to make such changes as properly fall within the scope of the appended claims.

Having described the invention what is claimed is:—

100 1. In a bowling alley, pins, a spring actuated hoisting lever for each pin, a cable connected to each pin and operatively connected with the hoisting lever, whereby when the lever is actuated the pin will be raised, means 105 to normally hold the lever in position to permit the pin to remain in lowered position, means controlled by impact upon the pin to release the hoisting lever holding means, a cable connected to the hoisting lever releasing means, a common actuating member for said cables to simultaneously actuate all of the hoisting lever releasing means and reset the hoisting levers, and means to operate the common actuating member and reset the pins. 115

110 2. In a bowling alley, pins, a spring actuated hoisting lever for each pin, a cable connected to each pin and operatively connected with the hoisting lever, whereby when the lever is actuated the pin will be raised, means 115 to normally hold the lever in position to permit the pin to remain in lowered position, a combined release and resetting lever, means located in the path of movement of the last mentioned lever to actuate the hoisting lever holding means when the pin is subjected to impact, a cable connected to the combined release and resetting lever, and means to simultaneously operate all of the cables to reset the hoisting levers and reset the pins. 125

3. In a bowling alley, pins, a cabinet located above the pins and having openings in the bottom, cables having one of their ends connected to each pin and extending through the 5 openings with the other ends of the cables anchored within the cabinet, a pivotally mounted spring actuated hoisting lever for each cable to operate the cable and raise the pins, means to limit upward movement of the pins 10 under the action of the hoisting levers,

weighted latches normally engaging the levers to hold the latter in inactive position, a releasing lever for each latch, means carried by the latches for engagement by the releasing lever to actuate the latch and release the 15 hoisting lever when the pin is subjected to impact, and means to actuate the releasing levers to reset the hoisting levers and reset the pins.

In testimony whereof I affix my signature.

RUSSELL CLINE ROSHON.
